UNITED STATES PATENT OFFICE.

WILLIAM MEYER, OF ROSEDALE, KANSAS.

CHANGE MAKER.

1,413,756.

Specification of Letters Patent. Patented Apr. 25, 1922.

Application filed January 28, 1920. Serial No. 354,688.

To all whom it may concern:

Be it known that I, WILLIAM MEYER, a citizen of the United States, residing at Rosedale, in the county of Wyandotte and 5 State of Kansas, have invented certain new and useful Improvements in Change Makers, of which the following is a specification.

My invention relates to change makers and while it is capable of general use it is particularly useful for street car conductors who have occasion to frequently make 10 change.

The invention embodies a series of coin magazines, ejectors for delivering coins from 15 said magazines, independent keys for actuating the respective ejectors, and mechanism for connecting the keys at will, so that any number of said keys may be simultaneously actuated to deliver change in different 20 amounts.

In order that the invention may be fully understood, reference will now be made to the accompanying drawings, in which:

Fig. 1 is a front elevation of the change 25 maker.

Fig. 2 is a plan view.

Fig. 3 is an end elevation.

Fig. 4 is an elevation of a rockable shaft and a plurality of keys associated with said 30 shaft.

Fig. 5 is a fragmentary elevation of the parts disclosed on Fig. 4, with the rockable shaft rotated approximately one-fourth of a revolution.

Fig. 6 is an irregular horizontal section on line VI—VI of Fig. 1.

Fig. 7 is a vertical section on line VII of Fig. 1.

Fig. 8 is a detail perspective of one of the 40 coin ejectors.

In carrying out the invention, I employ a series of magazines 2, 4, 6, 8, and 10, respectively, connected at their upper ends by a plate 12 and at their lower ends by a plate 45 14. The plates 12 and 14 are assembled in a frame 16 embodying a top plate 18 overlying the plate 12, a bottom plate 20 spaced a slight distance below the plate 14, as more clearly shown on Fig. 7, and a back plate 21 uniting the plates 18 and 20. The top plate 18 has a series of coin slots 22, 24, 26, 28 and 30 communicating with the upper open ends of the 50 magazines 2, 4, 6, 8 and 10, respectively. The bottom plate 20 has a series of discharge 55 openings 32, 34, 36, 38 and 40 underlying the

rear portions of the lower open ends of the magazines 2, 4, 6, 8 and 10, respectively. The front portions of the magazines have eight openings 41, so that it can be readily determined when they are nearly emptied of 60 coins.

A series of coin ejectors 42, 44, 46, 48 and 50 are slidably mounted in the space 52 between the plates 14 and 20, said space 52 being divided by partitions 54 which space 65 the ejectors apart. Each coin ejector consists of a rectangular plate having a circular opening extending therethrough and approximately the same size as the internal diameter of the coin magazine under which 70 the ejector is slidably mounted. In the present instance the coin ejector 44 is made thick enough to receive and eject two coins at the same time.

55 designates a hopper secured to the 75 plates 16 and 20 and underlying the discharge openings 32, 34, 36, 38 and 40 in the plate 20, to direct the ejected coins into the hand of the operator.

56 designates a rockable shaft journaled 80 in segments 58 removably secured to the back plate 21 of the frame 16, by suitable means such as screws 59. The rockable shaft 56 is provided at one end with a fixedly mounted lever 60, having a lug 62 adapted to enter 85 either of slots 64, 66, in the segment 58 at the left end of the frame 16. 68, 70, 72, 74 and 76 designate a series of keys provided with tubular clutch members 78, 80, 82, 84 and 86, respectively, freely mounted upon the 90 rockable shaft 56. The lower ends of the keys project into slots 87 in the respective coin ejectors for the purpose of actuating the same and to permit lateral movement of 95 said keys, as will hereinafter appear.

The rockable shaft 56 is provided with studs 90, one of which is disposed between the adjacent ends of each pair of clutch members, as disclosed on Figs. 4 and 5. The studs 90 are so located and the clutch members 100 on which they act are so shaped that each clutch from left to right is moved a less distance than the preceding one. Hence when the shaft 56 is rocked to the position disclosed on Fig. 5, the clutches are separated from each other and release each key for independent movement. Said shaft 56 is also provided adjacent its ends with studs 92 and 96, engaging cams 98 and 100 on the keys 68 and 76, respectively, to force the 105 110 keys 68 and 76, respectively, to force the

clutch members 78 to 86, inclusive, into engagement with each other when the shaft 56 is rocked in one position and to limit the longitudinal movements of said clutch members when the same are forced apart by the studs 90.

Springs 102 coiled upon the clutch members and engaging the back plate 21 of the frame 16 and the lower portions of the respective keys, normally hold said lower portions in forward position, so that they in turn will hold the ejectors against a stop 104, turned on the forward margin of the bottom plate 20, as disclosed on Fig. 7. Backward movement of the coin ejectors is limited by the back plate 21 of the frame 16.

In practice, the coin magazines are made in different diameters to receive coins of different sizes and values. In the present instance, the magazines 2, 4, 6, 8 and 10 are of proper diameter to receive metal checks or tokens, one cent, five cent, ten cent, and twenty-five cent pieces, respectively. Coins of any desired denomination may be substituted for the metal checks in the coin magazine 2, but when the machine is used by street car conductors said magazine is, preferably, supplied with checks each of which is equal in value to one fare.

When it is desired to operate the keys individually, the rock shaft 56 is rotated approximately a quarter of a revolution by swinging the lever 60 from the full line position down to the dotted line position on Fig. 3. This causes the studs 90 to move downwardly and force the clutch members laterally out of engagement with each other as disclosed on Fig. 5, so that any one of the keys may be actuated without operating the companion keys. When simultaneous operation of two or more keys is desired in order to eject coins from two or more magazines at the same time, the lever 60 is adjusted to the full line position disclosed on Fig. 3, which operation raises the studs 90 out of engagement with the clutch members and causes the studs 92 and 90 to act on the cams 98 and 100, and cause them to throw the clutch members into engagement as disclosed on Fig. 4. Assuming that the fare is eight cents and a passenger hands the conductor ten cents, the latter actuates the key 70, which through the intermediary of the clutch members, actuates the key 68 and causes the ejectors 44 and 14, respectively, to deliver a check with which to pay the fare and two cents change. If the conductor receives twenty-five cents, he actuates the key 74 which in turn simultaneously actuates all of the keys to the left and results in the delivery of ten cents, five cents, two cents, and an eight cent check. If the conductor receives fifty cents, he actuates the key 76, which in turn simultaneously actuates all of the keys to the left and results in the de-

livery of a twenty-five cent piece, a ten cent piece, a five cent piece, two cents, and an eight cent check.

Other combinations to suit other than eight cent fares can be substituted for the one just described, and additional magazines with associated mechanisms can be added to increase the capacity of the machine without departing from the spirit and scope of the invention as defined in the appended claims.

Having thus described my invention, what I claim and desire to secure by Letters Patent, is:

1. A change making machine consisting of a series of coin magazines, coin ejectors associated with the respective magazines, keys arranged to be operated independently of each other and associated with the ejectors to cause them to deliver coins from the respective magazines, interlocking means whereby any number of keys can be simultaneously actuated through the operation of a single key, and means for throwing said interlocking means in and out of operation.

2. A change making machine, consisting of a series of coin magazines, coin ejectors associated with the respective magazines, keys arranged to be operated independently of each other and associated with the ejectors to cause them to deliver coins from the respective magazines, resilient means to restore the keys and the ejectors to normal position after coins have been delivered, and rotary interlocking means whereby any number of keys can be simultaneously actuated through the operation of one of the aforementioned keys.

3. A change making machine consisting of a series of coin magazines, coin ejectors associated with the respective magazines, keys arranged to be operated independently of each other and associated with the ejectors to cause them to deliver coins from the respective magazines, an adjustable shaft on which said keys are operably mounted, interlocking means whereby any number of keys may be operated in unison, and elements on the shaft to adjust said interlocking means to active and inactive positions.

4. A change making machine consisting of a series of coin magazines, coin ejectors associated with the respective magazines, keys arranged to be operated independently of each other and associated with the ejectors to cause them to deliver coins from the respective magazines, an adjustable shaft on which said keys are operably mounted, clutch means fixed to said keys and whereby any number thereof may be operated in unison, and elements fixed to the shaft and adapted to adjust said clutch means in and out of engagement.

5. A change making machine consisting of a series of coin magazines, coin ejectors

associated with the respective magazines, keys arranged to be operated independently of each other and associated with the ejectors to cause them to deliver coins from the respective magazines, a rockable shaft on which said keys are operably-mounted, clutch means associated with said keys and whereby any number thereof may be operated in unison, and elements fixed to the rockable shaft to adjust said clutch means to active and inactive positions.

6. A change making machine consisting of a series of coin magazines, a plate connecting the upper ends of said magazines and provided with coin slots leading into the respective magazines, a hopper disposed below the magazines, coin ejectors associ-

ated with the respective magazines, keys arranged to be operated independently of each other and associated with the ejectors 20 to cause them to deliver coins from the respective magazines, interlocking means whereby any number of keys can be simultaneously actuated through the operation of a single key, and means for throwing 25 said interlocking means in and out of operation.

In testimony whereof I affix my signature, in the presence of two witnesses.

WILLIAM MEYER.
